UNITED STATES PATENT OFFICE

CHESTER E. RAHR, OF BROOKLINE, MASSACHUSETTS, ASSIGNOR, BY MESNE ASSIGNMENTS, TO THE PATENT AND LICENSING CORPORATION, OF BOSTON, MASSACHUSETTS, A CORPORATION OF MASSACHUSETTS

ROOFING

Application filed March 2, 1926. Serial No. 91,839.

This invention relates to a method of manufacturing roofing elements, an object of the invention being to provide a simple and convenient way of making shingle strips which when laid will present the appearance of having spaces between consecutive shingle simulating portions. The method comprises coating a roofing base which may comprise a sheet of saturated felt or other suitable material with asphaltum or other similar compound, as is commonly practised in the art. On the coated surface of the base is laid a template or cut-out sheet of any suitable material such as thin asbestos, saturated felt, untreated paper, or glazed, waxed, or oiled paper. Comminuted material, such as grit, of any desired color, or electrically conductive particles, is then deposited on or otherwise applied to the sheet and embedded in the exposed areas of coating by any of the methods well known in the art, such as by press rolls or by tension of the sheet over drums. The template prevents the grit from sticking to the covered portions of the coated surface of the sheet. The sheets are then cut into the usual strip form, the pattern of the template being so arranged that the covered or upper portion of each strip when laid will be surfaced with a portion of the template, while the exposed or lower part of the strip will exhibit a row of grit-covered areas separated by areas or stripes of the template material. This material may be such that it will soon wash off from the exposed part of the shingle strip after the roof is laid, leaving black lines between the grit-covered areas, or it may be such as will resist the action of the weather. A variety of effects are furthermore obtainable by using templates of colors contrasting with that of the grit. These effects may be temporary or, by the use of weatherproof material such for example as coated paper or felt for the template, such effects may be made permanent.

If it is desired to coat the shingle strip with metal such as copper, the template may be of oiled or glazed paper to prevent the adhesion of the graphite or other comminuted conductive material which may be applied to the sheet, the copper plating thus being confined

to the areas not covered by the template. If a continuous coating of copper be desired for the exposed portion of the unit, the template may be made of a material, e. g. saturated felt, to which graphite will adhere, but which will not hold grit to its surface. In this case, the areas covered by the template would receive a smooth coating of copper contrasting with the raised and irregular surface deposited on the areas covered by the layer of conductive grit. Graphite or conducting material may be applied, if desired, to the lower edge of the strip after cutting and before plating, so that the copper coat will also cover the cut edge, but this is not essential.

The roofing strip produced by this invention is light and strong, has a pleasing appearance, has excellent protective qualities, and is easily and economically manufactured.

On the drawing,—

Figure 1 represents a fragment of a sheet of material for the template.

Figure 2 shows the same fragment after the desired pattern has been cut.

Figure 3 shows the fragmental template applied to a corresponding fragment of a saturated and coated sheet of roofing felt.

Figure 4 shows a single strip cut from the sheet.

Figure 5 is a section on the line 5—5 of Figure 4.

Figure 6 shows a pattern arranged for longitudinal cutting.

Referring to the drawing in detail, 10 represents a fragmentary portion of a sheet of material suitable for a template, such as thin asbestos paper or the like. This sheet is preferably of the same width as the sheet of roofing material to which it is to be applied. Any desired pattern is cut or stamped out of the sheet 10, one form being shown in Figure 2 and comprising transverse rows of perforations 11 separated by relatively narrow stripes 12, the rows being spaced by portions 13 of the sheet 10. As illustrated in Figure 6, the template may also be designed so as to dispose the units to be cut from the sheet longitudinally thereof. In either case, the template may be designed and the sheet cut so that the stripes at the ends of the units

will be one-half the normal width, as shown in Figure 6.

A sheet of saturated roofing felt 14 or other suitable material may have a coating 15 of adhesive material which may be bituminous, such as blown asphalt or other thermoplastic waterproofing compound applied thereto, followed by the template sheet which will cover and adhere to part of the coated area, 10 leaving parts exposed through the cutouts 11. Comminuted material, such as grit or its equivalent, may be deposited on the sheet and rolled in by suitable press rolls known to the art. Particles of the grit will adhere to and 15 cover the areas not covered by the template, but the areas covered by the template will be kept free from grit. If it is desired to electroplate the strip with a metal such as copper, an electrically conductive material 16 may be substituted for the grit, such for example, as carbon crystals, graphite, granules, coke electro-conductive grits or a mixture of any of these. In case the template is made of oiled paper or any other non-conducting material 20 to which graphite will not readily adhere, the stripes 12 will not receive a deposit of metal when the unit is dipped in the electrolytic bath, but the film of metal 17 will be confined to the areas not covered by the template. It 25 may be desirable, however, to plate with copper the entire exposed portion of the unit, in which case the template is preferably of some material, such as saturated felt, to which graphite will adhere while grit will not. Application of graphite and conductive grit to 30 the sheet will thus result in a thin smooth layer of graphite on the template and a thick layer of grit on the areas not covered by the template. The grit gives these areas a raised, 35 rough surface, which is substantially reproduced by the film of metal deposited in the electrolytic bath. Thus the exposed portion 40 of the unit (which may be the extent to which the unit is immersed in the electrolyte) is wholly covered with a continuous film of 45 metal, the film on the template-covered areas being of contrasting smoothness, and lower than the grit-covered areas. By this latter process, it is possible to have a metal-plated 50 shingle strip having shingle-simulating portions set off by contrasting stripes, but avoiding the undesirable feature inherent in such a strip when made with actual cut-outs between the shingle-simulating areas, namely, the liability 55 of the film of copper to crack above the cut-out when the strip is flexed. It is to be understood that the "exposed portion" of a roofing unit, as used in the specification and claims, refers to that portion of the surface of 60 a unit which when laid on a roof will normally be exposed to the weather.

The sheet with its coated surface covered partly by the template and partly by comminuted material may be cut into strips by 65 any suitable means with reference to the pat-

tern of the template. As shown in Figure 3, these cuts may be made transversely of the sheet through each row of perforations 11 and through the portions 13 of the template which space the rows of perforation. This 70 may produce a strip of roofing as shown in Figure 4, the upper portion of which is covered by the thin asbestos, paper or equivalent material, but free from grit. The lower portion which will be exposed to the weather 75 when the roof is laid, gives the appearance of separate slated shingles, the grit-coated areas being spaced by the stripes 12 of the template. These exposed stripes if of asbestos or untreated paper will ordinarily wear off with 80 the weather, leaving stripes of black coating between the grit-covered areas. The template may, however, be made of more durable material, such as saturated felt or coated felt or paper, in which case the template 85 would present a durable surface to the weather. A variety of color effects may also be obtained by the use of suitable materials. For example, the template may be made of a saturated paper coated with stearine pitch 90 mixed with a pigment such as red oxide. By selecting a grit of suitable contrasting color, permanent and pleasing effects are readily obtainable.

The patterns of the template shown in the 95 drawing are for the purposes of illustration only, and while they are preferred forms, the invention is not to be limited thereto, but may include any size, shape and arrangement of cut-outs.

I claim:

1. The method of making roofing which comprises applying a template to a coated sheet of prepared roofing material, depositing comminuted material on said sheet, and cutting the sheet with reference to the pattern of the template into strips.

2. The method of making roofing which comprises coating a sheet of roofing base with a waterproofing compound, cutting a template and applying it to the coated surface of said sheet, depositing comminuted material on said sheet, embedding said comminuted material in the surface of the coated areas not covered by the template, and cutting the combined sheet and template into strips, the cuts being so arranged with reference to the pattern of the template that each strip will have a row of areas covered with comminuted material separated by portions of the template.

3. The method of making roofing which comprises coating a sheet of roofing base with a thermo-plastic waterproofing compound, cutting a template with spaced rows of perforations arranged transversely of the sheet, applying said template to the coated surface of said sheet, depositing comminuted material on said sheet, embedding said material in the surface of the coated areas not covered

- by the template, and cutting the sheet transversely through each row of perforations.
4. The method of making roofing which comprises coating a sheet of roofing base with
- 5 a waterproofing compound, cutting a template of non-conductive material and applying it to the coated surface of the sheet, depositing comminuted electrically conductive material on the coated areas not covered by
- 10 the template, cutting said sheet into strips, and electro-plating the areas covered by said conductive material. 75
5. The method of making roofing which comprises coating a sheet of roofing base with
- 15 15 a waterproofing compound, cutting a template of electrically non-conductive material and applying it to the coated surface of the sheet, depositing comminuted electrically conductive material on the coated areas not
- 20 covered by the template, and electro-plating the areas covered by said conductive material. 80
6. The method of making roofing which comprises coating a sheet of prepared roofing
- 25 25 felt with a waterproof compound, cutting a template with spaced rows of rectangular perforations, applying the template to the coated surface of said sheet, depositing comminuted material on the coated side of said
- 30 sheet, embedding said material in the surface of the uncovered coated areas, and cutting the sheet transversely through each row of perforations. 85
7. A roofing strip comprising a roofing
- 35 base, a coating of waterproof compound over one side of said base, a template having cut-out portions adhering to and covering a part of said coating, comminuted electrically conductive material adhering to the areas of
- 40 coating not covered by said template, and a film of electrolytic metal overlying said material. 90
8. The method of making roofing which comprises coating a sheet of roofing base with
- 45 45 a waterproofing compound, cutting a template and applying it to the coated surface of said sheet, applying a layer of electrically conductive powder to the template, applying an electrically conductive layer comprising
- 50 grit-like particles to the areas not covered by the template, cutting the sheet into units, and depositing a film of metal in a continuous sheet on the entire exposed surface of the unit. 95
- 55 9. A roofing unit comprising a strip of roofing base, a layer of waterproof coating material on one face thereof, a template adhering to the coated face of the unit, comminuted material embedded in the surface of
- 60 the coating not covered by the template, and a continuous film of electrolytic metal overlying and completely covering the exposed surface of the unit. 105
10. A roofing unit comprising a strip of
- 65 coated roofing base, the exposed surface of 110
- 115
- 120
- 125
- 130
- said unit being plated with a film of metal and presenting areas of rough metal surface separated by areas of relatively smooth metal surface.
- In testimony whereof I have affixed my 70 signature.
